WATER HEATER AND THE LIKE

Cuthbert L. Dixon, Dunkirk, N. Y.

Application May 28, 1943, Serial No. 488,920

3 Claims. (Cl. 122—267)

This invention relates to improvements in hot water heaters, steam boilers and the like, and has for one of its objects to provide a practical, desirable and efficient water or fluid heater of improved novel construction.

Other objects of the invention are to produce a water or fluid heater which is of such construction that maximum capacity and heating efficiency are obtained in a heater of moderate size, compact and economical construction; which is a simple and inexpensive construction, provides a maximum area of heating walls arranged so as to most efficiently apply or utilize the heating medium and secure direct and intimate contact with said walls of the products of combustion or other heating medium and the water or fluid to obtain the maximum transfer of heat from one to the other.

Further objects and advantages of the invention will appear from the following specification of the preferred embodiment of the invention, shown in the accompanying drawing, and the novel features of the invention are set forth in the appended claims.

In said drawing:

Fig. 1 is a transverse sectional elevation on line 1—1, Fig. 2 of a heater embodying my invention.

Fig. 2 is a longitudinal sectional elevation thereof on line 2—2, Fig. 1.

Fig. 3 is a transverse, sectional elevation thereof on line 3—3, Fig. 2.

In the preferred construction shown in the drawing, which illustrates the device as more particularly designed for heating water, the heater is built with upper and lower main sections or portions 10 and 11 located one above and upon the other. Said upper section comprises opposite, or front and rear, upright hollow headers 14 and 15 connected by horizontal or nearly horizontal outer and inner tubes 16 and 17 which are arranged concentrically, or one lengthwise within the other. The opposite open ends of the outer tubes 16 are joined by suitable fluid-tight joints with the inner or facing walls 18 of the opposite headers 14 and 15, so that these tubes form a plurality of passages communicating with the header chambers through which fluid can flow from one header to the other. The inner tubes 17 extend through the opposite, hollow headers with their opposite open ends joined by suitable fluid-tight joints to the outer walls 19 of the two headers, thereby forming a plurality of open-ended passages extending completely through the heater section 10 for the passage of products of combustion or other fluid heating medium lengthwise through the heater section.

Likewise, the lower heater section 11 comprises opposite end or front and rear hollow headers similarly connected by a plurality of outer and inner tubes 16 and 17, but preferably said lower

section is made with a pair of spaced front headers 20 and 21 and a single rear header 22.

The two front headers 20 and 21 are located at opposite sides of a central fire box or burner chamber 23 of the casing for the tubular heater, in which the fuel for the heater is burned, and the heating tubes 16 and 17 of this lower section 11 are disposed in separated groups extending at opposite sides of the fire box from the two front headers 20 and 21 to the rear header 22. As shown, a partition divides the left front header 20 into lower and upper chambers 24 and 25, and a horizontal partition divides the rear header 22 into lower and upper chambers 26 and 27, so that the water or fluid to be heated, which may enter the lower chamber 24 of the left front header through a suitable inlet pipe connection 28, will flow rearwardly from this chamber through the connecting tubes 16 at the left side of the fire box to the lower rear header chamber 26, then across in this chamber and forwardly through the connecting tubes 16 at the right side of the fire box to the right hand front header 21, thence rearwardly from the upper portion of this header through higher tubes 16 at the right side of the fire box to the upper rear header chamber 27, across in this chamber and forwardly through the higher connecting tubes at the left side of the fire box to the upper chamber 25 of the left hand front header 20.

Front header 14 of the upper section 11 of the heater, as shown, is divided by horizontal and vertical partitions into two lower chambers 28, 29, and two upper chambers 30 and 31, while the rear header 15 of the upper section is shown as divided by partitions into lower and upper chambers 32, 33, and a single end chamber 34. The fluid passes from the upper chamber 25 of the left front header 20 of the lower section through a suitable connection 35 into the lower left chamber 28 of the front header 14 of the upper section. From the chamber 28, the fluid will circulate back and forth through different groups of tubes 16 and connecting header chambers of the upper heater section, thus passing through the tubes and chambers 32, 29, 34, 30, 33 in the order recited, to the upper left hand chamber 31 of the front header 14 from which the fluid will discharge through a suitable outlet connection and pipe 36 which may lead to one or more radiators or the like (not shown) from which the fluid can return to inlet connection 28 for recirculation through and reheating in the heater.

Thus, the water or fluid to be heated will circulate back and forth through the headers and different groups of tubes 16 at opposite sides of the fire box in the lower heater section and then back and forth through the headers and different groups of tubes 16 of the upper heater section located above the fire box 23, and will be

heated by heat from the fire box and the hot gases or products of combustion which pass from the fire box through the spaces between the tubes 16, thereby contacting with and sweeping over the outer surfaces of the tubes and externally heating the tubes, through which circulates the fluid to be heated. In addition, the hot gases are also caused to flow through the inner tubes 17 on their way to the smoke pipe or chimney, and since the water or fluid being heated is divided into numerous relatively thin streams or bodies in the annular spaces between the several inner and outer tubes, a rapid and maximum transfer of heat is effected from the heating medium to the medium being heated.

For thus causing the hot gases to pass through the inner tubes 17, the outer casing 40 in which the tubular heater, organized as above explained, is housed, has incorporated therein, in the construction illustrated in the drawing, transverse partition walls 41 and 42, in which the front and rear headers of the heater sections are set, and which divide the interior of the casing into a central chamber 43 and end or front and rear chambers 44 and 45. The central chamber 43 communicates with the fire box or burner chamber 23, and at its upper portion communicates with the front chamber 44 over the top of the wall 42, but is shut off by wall 41 from the rear chamber 45, which leads to the smoke pipe or chimney. The tubes 16 of the upper heater section are located in or pass through the central chamber 43. Therefore, the draft created by the chimney will cause the hot gases to pass from the fire box up through the central chamber, between and around the various tubes 16, and from the upper portion of the central chamber into front chamber 44, from which the hot gases will be drawn through several inner tubes 17 to the rear chamber 45, and thence to the chimney or smoke stack. Any other appropriate formation of the heater casing or housing, or other means, could be employed to cause the hot gases to flow through the inner tubes 17 as well as around or over the outer tubes 16 for heating the water or fluid circulating through the outer tubes.

If solid fuel is to be used as the heating medium, a suitable fire pot and grate can be provided in the fire box or chamber 23, or the fire box otherwise appropriately constructed to contain or confine the fuel, but such will not be necessary if a fluid fuel burner is employed as the heat producing means.

When the fluid heater constructed as disclosed, is to be employed as a boiler or steam generator, a steam drum or upper steam chamber may be incorporated in the device in communication with the water space of the tubular heater. The purpose and arrangement of such steam drums are well known and detailed disclosure of the same herein is believed unnecessary. When more heating area is required or necessary, additional, suitable heater sections can be added, by placing them with their headers on top of the headers of the various sections shown on the drawing.

I claim as my invention:

1. In a heater for fluids comprising a casing having a fire chamber in its lower central portion, and a tubular structure housed in the casing including opposite hollow headers, substantially horizontal outer tubes connecting said headers and forming passages for the flow of the fluid from one header to another, and an inlet and an outlet for the fluid, the improved construction

in which said tubular structure comprises a lower portion having spaced headers at one end and groups of tubes at opposite sides of said fire chamber and a single header at its opposite end, an upper portion with one header at each end and connecting tubes located over said fire chamber, said headers being constructed to cause the fluid to circulate from said inlet through said headers and tubes to said outlet, inner tubes extending through said outer tubes and through the opposite headers and open at their opposite ends for the passage of gases therethrough, and means forming chambers in said casing constructed and arranged to cause hot gases from said fire chamber to pass between and around said outer tubes and then pass through said inner tubes.

2. In a heater for fluids comprising a casing having a fire chamber in its lower central portion, and a tubular structure housed in the casing including opposite hollow headers, substantially horizontal outer tubes connecting said headers and forming passages for the flow of the fluid from one header to another, and an inlet and an outlet for the fluid, the improved construction in which said tubular structure comprises a lower section and an upper section above and supported on the lower section and having a fluid passage connection therewith, said lower section having at one end spaced headers located at opposite sides of said fire chamber, a single header at its opposite end, and spaced groups of tubes connected with said headers, and said upper section having headers at opposite ends and connecting tubes located over said fire chamber, said headers being constructed to cause the fluid to circulate from said inlet through said headers and tubes to said outlet, inner tubes extending through said outer tubes and through the opposite headers and open at their opposite ends for the passage of gases therethrough, and means forming chambers in said casing constructed and arranged to cause hot gases from said fire chamber to pass between and around said outer tubes and then pass through said inner tubes.

3. In a heater for fluids comprising a casing having a fire chamber in its lower central portion, and a tubular structure housed in the casing including opposite hollow headers, substantially horizontal outer tubes connecting said headers and forming passages for the flow of the fluid from one header to another, the improved construction in which said tubular structure comprises spaced lower header portions and different groups of said tubes located at opposite sides of said fire chamber, upper header portions with connecting tubes located over said fire chamber, a fluid inlet on one of said lower spaced header portions and a fluid outlet on one of said upper header portions, said headers being constructed to cause the fluid to circulate from said inlet first through said lower groups of tubes and then through said tubes over the fire chamber to said outlet, inner tubes extending through said outer tubes and through the opposite headers and open at their opposite ends for the passage of gases therethrough, and means forming chambers in said casing constructed and arranged to cause hot gases from said fire chamber to pass between and around said outer tubes and then pass through said inner tubes.

CUTHBERT L. DIXON.
